UNITED STATES PATENT OFFICE.

WALTER E. HASSAM, OF WORCESTER, AND HAROLD PARKER, OF LANCASTER, MASSACHUSETTS, ASSIGNEES TO HASSAM PAVING COMPANY, A CORPORATION OF MASSACHUSETTS.

METHOD OF MAKING PAVEMENT.

1,191,303.

Specification of Letters Patent. Patented July 18, 1916.

No Drawing.

Application filed August 1, 1912. Serial No. 712,803.

To all whom it may concern:

Be it known that we, WALTER E. HASSAM and HAROLD PARKER, citizens of the United States, respectively, residing at Worcester and Lancaster, both in the county of Worcester and State of Massachusetts, have invented a new and useful Method of Making Pavement, of which the following is a specification.

10 This invention relates to an improved method of making the pavement shown, described and claimed in the application for patent filed on even date herewith, by the said Walter E. Hassam Serial No. 712672.
15 Said application for patent relates to an improvement on Letters-Patent granted to him May 1, 1906, No. 819,652 on a "Pavement and process of laying the same." By said patent he provides a pavement, by laying on the level road bed a layer or stratum of naked or uncoated stone; by rolling the stone in its uncoated or clean condition; by applying a grout to fill the voids therein; and by placing a suitable wearing surface 20 thereon. The improvement contained in said application for patent consists in substance in providing a concrete foundation or pavement of the character shown, described and claimed in said patent, with a smooth or top surface, and in applying a thin layer of hot bitumen thereto, which bituminous layer is drifted and rolled with screened pea stone or suitable sand or gravel.

In experimenting with the improvement 35 of said application, we have discovered that the bituminous layer can be caused to adhere much closer to the concrete foundation if the same is applied thereto under pressure. This we attribute to the fact that by 40 applying the hot bitumen to the concrete foundation in small jets under heavy pressure, all dust or loose particles are swept aside, air bubbles prevented, and if the concrete foundation is left or made slightly 45 moist, when the hot bitumen is applied under pressure, an action takes place which causes a very firm adherence.

The improved method is practised as follows:—The road which is to receive the pavement is first leveled off or prepared and brought to a solid sub-grade of exact cross-section by rolling or tamping, as may be necessary. Then on this road a layer or

stratum of uncoated broken stone of about 55 from one and one-half inches to two and one-half inches in diameter is laid so that it will have a uniform thickness. This layer of uncoated stone is then rolled with a heavy roller, or otherwise compressed in its naked or uncoated condition to reduce the voids 60 therein to a minimum, to get the stones into as intimate contact with each other as possible, and to get as much stone into a given thickness as possible. This rolling and compacting is carried on until a stone layer of 65 suitable thickness is provided. A thin grout consisting of Portland cement, one part; sand, two or more parts; and enough water to form a creamy consistency is then poured upon the stone layer until all the voids 70 therein are filled and until the grout flushes to the surface. During this step, or immediately thereafter, the stone layer is lightly rolled or compressed to obtain as smooth and even top surface as is possible (and to 75 force the grout into every portion of the mass). The foundation or concrete thus formed is allowed to set until it becomes hard (and thoroughly set) with a very smooth even top surface. This top surface 80 is then slightly moistened with water. Then the smooth moistened top surface of the concrete is covered with a very thin layer of bitumen or bituminous compound heated to a temperature of between 200 and 300 degrees F., and applied in fine jets under pressure. This application can be made by any suitable spraying and pressure machine and is preferably carried on by a pumping spraying machine having nozzles arranged five 85 to ten inches above the ground and having a pump or other means of applying pressure which will force the hot bitumen out through the nozzles in jet form at about 80 pounds pressure. This application of hot bitumen 90 under pressure to the concrete foundation, will cause a very firm adherence of the bitumen to the concrete. Immediately after this thin bituminous coat is applied, the same is drifted with screened pea stone or 95 suitable sand or gravel and rolled with a light roller, sufficient stone, sand or gravel being applied to absorb any surplus bitumen. A plurality of layers of bitumen and sand, 100 stone or gravel preferably are applied in this manner so as to make up a mat or wearing 105

top from one-fourth to one-half inch in thickness on the top of the smooth concrete foundation.

The particular point of the present improvement consists in the application of the hot bituminous layer under pressure, to a concrete foundation preferably having a smooth top surface, and preferably slightly moistened, so as to obtain a very close adherence between the bituminous surface and the concrete.

By this method of construction, a superior wearing surface can be produced because the hot bitumen can be very quickly applied, as only a very thin (and uniform) layer is required; and the method is very economical, because only a relatively small amount of bitumen is needed, even if a plurality of layers are applied. The pavement thus constructed has the great rigidity and strength of concrete, and has additionally, an inexpensive resilient wearing surface which is practically dustless, which gives the proper grip for wheels and horses, and which can be very readily repaired.

The proportions herein specified may be

varied by a skilled engineer without departing from the scope of our invention as expressed in the claims.

Having thus fully described our invention, what we claim and desire to secure by Letters-Patent is:—

1. The method of making a pavement, which consists in laying a concrete foundation, moistening the same, and applying one or more thin layers of hot bitumen to the foundation under pressure.

2. The method of making a pavement, which consists in laying a concrete foundation, moistening the same, applying one or more thin layers of hot bitumen to the same under pressure, and rolling sand, pea stone or gravel into the bituminous layer.

In testimony whereof we have hereunto set our hands, in the presence of two subscribing witnesses.

WALTER E. HASSAM.
HAROLD PARKER.
